United States Patent Office

Des. 202,832
Patented Nov. 9, 1965

202,832

MOTION PICTURE CAMERA

Richard J. Olson, Pittsford, N.Y., assignor to Eastman
Kodak Company, Rochester, N.Y., a corporation of
New Jersey

Filed Mar. 31, 1965, Ser. No. 84,540

Term of patent 14 years

(Cl. D61—1)

FIG. 1

FIG. 2

FIG. 3

FIG. 4

FIG. 5

FIG. 6

FIG. 1 is a front perspective view of a motion picture camera showing my new design with the hand grip lowered to its operative position;

FIG. 2 is a rear perspective view thereof;

FIG. 3 is a view similar to FIG. 1 but showing the hand grip retracted;

FIG. 4 is a rear perspective view thereof;

FIG. 5 is a bottom view corresponding to FIG. 4; and FIG. 6 is a bottom view corresponding to FIG. 2.

I claim:

The ornamental design for a motion picture camera, as shown.
